CLAIM

The ornamental design for a light for cosmetic application, as shown and described.

DESCRIPTION

FIG. 1 is a front left oblique view of a light for cosmetic application showing my new design,

FIG. 2 is a front right oblique view thereof,

FIG. 3 is a back left oblique side view thereof,

FIG. 4 is a back right oblique side view thereof,

FIG. 5 is a bottom left oblique side view thereof,

FIG. 6 is a left side view thereof,

FIG. 7 is a right side view thereof;

FIG. 8 is a back side view thereof;

FIG. 9 is a front side view thereof;

FIG. 10 is a top side view thereof; and,

FIG. 11 is a bottom side view thereof.

The broken lines depict portions of the light for cosmetic application that form no part of the claim.
